 LLP

(57) **CLAIM**

The ornamental design for a portable power cleaner, as shown and described.

DESCRIPTION

FIG. 1 is a perspective view of a portable power cleaner showing our new design;

FIG. 2 is a right side elevational view of the portable power cleaner of FIG. 1;

FIG. 3 is a left side elevational view of the portable power cleaner of FIG. 1;

FIG. 4 is a front elevational view of the portable power cleaner of FIG. 1;

FIG. 5 is a rear elevational view of the portable power cleaner of FIG. 1;

FIG. 6 is a top plan view of the portable power cleaner of FIG. 1; and,

FIG. 7 is another perspective view of the portable power cleaner of FIG. 1 including an accessory.

The broken lines shown in the drawings illustrate portions of the portable power cleaner and the accessory that form no part of the claimed design.

1 Claim, 7 Drawing Sheets
